UNITED STATES PATENT OFFICE.

FREDERICK OATLEY BYNOE, OF ACTON, ENGLAND, ASSIGNOR TO HIGH TEMPERATURE GENERATORS LIMITED, OF LONDON, ENGLAND, A CORPORATION OF GREAT BRITAIN.

SUPERHEATER.

1,331,841.

Specification of Letters Patent. Patented Feb. 24, 1920.

Application filed March 28, 1917. Serial No. 158,109.

To all whom it may concern:

Be it known that I, FREDERICK OATLEY BYNOE, a subject of the King of Great Britain and Ireland, and resident of Acton, 5 county of Middlesex, England, have invented certain new and useful Improvements in and Relating to Superheaters, of which the following is a specification.

My invention of improvements in and relating to superheaters is directed to that type of superheater in which compound or double tubes are employed, that is to say, a tube within another, the inner tube opening into the outer which is sealed at one end, and 15 the object of my invention is to produce an improved superheater of this type.

My invention consists essentially of a double or compound tube formed by an outer tube containing an inner tapered tube placed 20 eccentrically, this arrangement being so disposed in connection with a header that the inner tube can be independently withdrawn from the outer tube for inspection of both outer and inner tubes without interfering 25 with any other of a series of tubes, or that an outer tube can be removed for inspection without interfering with those that remain. The invention also comprises flanged inlet and distributing header, flanged collecting 30 and outlet header, or a combined flanged inlet distributing header and flanged collecting outlet header, flanged return bends connecting each passage in an inlet header with the corresponding passage in an outlet header, 35 the outer tubes of the compound tubes being connected by their flanged ends to one face of the outlet header, while the inner tubes are connected to the outer face of the inlet header by return bends which carry said inner tubes, said inner tubes passing through 40 said outlet header into the outer tubes.

The following description together with the accompanying sheets of drawings will make clear the details and method of carrying out my invention.

I will first generally describe the figures only, a detailed description of which follows hereinafter.

Figure 1 is a sectional view showing a 50 flanged header and superheater tube constructed in accordance with the present invention, said superheater tube consisting of an outer cylindrical-shaped tube *a* sealed at

one end, containing a tapered inner tube *d* with its widest part at the open free end. 55

Fig. 2 is a sectional view of said superheater tube but shown detached.

Fig. 3 represents an outer tapered tube *a* with the widest end attached to a flange, and containing an inner tapered tube *d*. 60

Fig. 4 represents an outer tube *a* with an inner cylindrical parallel tube *d* placed within it.

Fig. 5 represents a cylindrical outer tube *a* with a tapered inner tube *d* placed eccentrically within it. 65

Fig. 6 represents a tapered outer tube *a* with a tapered tube *d* placed eccentrically within it.

Fig. 7 represents an elevation of the superheater tube and flanged header, shown in Fig. 1. 70

Fig. 8 is a plan view of Fig. 7.

Fig. 9 is an end view of Fig. 7.

Fig. 10 is a sectional drawing of a combination header, viz.; a distributing or inlet header combined with a collecting or outlet header. The distributing or inlet header *h* has a main passage, open at each end, with distributing passages leading out from one side only from the main passage. The collecting header *c* has a main passage, open, at each end, with collecting passages opening in line to opposite sides of the header. All openings are flanged for attachment to other parts. A flanged return bend *f* connects each passage in the inlet header *h* with the corresponding one in the outlet header *c*. One end of an inner tube *d* is fitted into the opening in the passage *b'* 80 in the return bend which is over the cross passage in the outlet header so that it projects through the other side of the header. An outer tube *a* is attached by its flange to the opening in the collecting header *c* through which the inner tube is projecting. 85

By this arrangement the use of separate distributing and collecting headers is obviated.

Fig. 11 is a side view of the combined inlet or distributing header with the combined outlet or collecting header with tubes attached. 95

Fig. 12 is a plan view of Fig. 11, showing a set of three tubes.

Figs. 13 and 14 are sections of a modified 105 means for connecting the inlet passage with

the entrance to the superheater tubes. In this form the flange f^2 carrying the inner tube d is separate from the part f' containing the connecting passage.

5 Fig. 15 illustrates the face of the flanged part represented in Figs. 13 and 14.

Fig. 16 illustrates the arrangement of headers in a series of superheater tubes with the type of header shown in Figs. 1, 7, 8 10 and 9.

Fig. 17 illustrates the arrangement of combined headers in a series of superheater tubes with the type of headers shown in Figs. 10, 11 and 12.

15 Figs. 18 and 19 are part sections of a removable cone and a thimble-shaped cover of refractory material used as a protection for the outer superheater tubes.

20 Fig. 20 is a vertical sectional view showing how a chamber superheater tube, its headers and flanged return bend are assembled.

Fig. 21 is an end view partly in section of said Fig. 20.

25 Fig. 22 is a plan view thereof partly in section.

30 Figs. 23 and 24 show how a circular superheater may be constructed in accordance with the invention; Fig. 23 being a vertical section and Fig. 24 being a horizontal section.

Referring in detail to the drawings, like letters are used to indicate the same parts.

35 In carrying out my invention, I construct an outer tube or chamber a —Fig. 1—which may have any sectional shape, sealed at one end a' , and at the other end a^2 opening into an outlet passage b in a flanged header c .

40 This flanged header c is provided with two passages separated from one another by a wall or diaphragm g , one passage being elbow-shaped and the other T-shaped, one end of the cross passage in the T opening on to the same side of the header as one of 45 the openings of the elbow-shaped passage, and to the side of said header c which presents the one opening only is attached by its slotted flange the outer tube a . To the other side of the header is attached by its 50 slotted flange a return bend f connecting the two openings, viz:—one end of the elbow passage with one end of the T passage. Into the passage of the return bend which covers the T passage in the header c is fitted 55 one end of the inner tube d , open at both ends d' , d^2 , the open end d' of said tube d reaching nearly to the closed end a' of the outer tube a . The other end d^2 is attached 60 to the above mentioned header c in such a manner that it terminates in an inlet passage b' in the header. Thus, an annular space e is produced between the inner and outer tubes.

65 By this construction, steam or vapor entering by way of the inlet b' in the header

c and into the inner tube d has to flow to the end d' of said inner tube and then pass by way of the annular space e between the inner and outer tubes to the outlet b , and as it is necessary that the sectional area of the 70 steam passage through the tubes shall gradually increase from inlet to outlet, I make the inner tube d —Figs. 1, 2 and 3—tapered with its largest end d' near the sealed end a' of the outer tube a . If it is desirable to 75 produce an increased variation between the sectional area of the inlet and the outlet, I also make the outer tube a —Fig. 3—tapered with its outlet end a^2 larger than the sealed end a' .

80 As the part of the superheater tubes through which the thickest sectional area of steam is flowing must be attacked by the hottest portion of gases from the furnace, I mount the inner tube d —Figs. 4, 5 and 6—85 eccentrically in the outer tube a in such a manner that the part of the outer tube which contains the greatest sectional area of the annular space e , i. e. that part of the outer tube where there is the widest space between it and the inner tube, is attacked by the fiercest heat, viz:—if the tubes are horizontal or oblique, the inner part contains the widest part of the annular space e , and if the tubes are vertical or staggered, that 90 side is placed in the direction of the approaching hot gases from the furnace.

95 The construction above mentioned provides that only the outer tube a is subjected to the destructive gases of the furnace and is the only part likely to require renewing through being burnt.

100 In order that the tubes may be easily examined, cleaned or renewed, I construct a combined inlet and outlet header c —Figs. 1 and 7 to 17—in such manner that the inner tube d is attached to a flanged return bend f —Fig. 1—having an internal passage b' , one end—Fig. 1—of which opens into the inner tube, while the other end opens into an inlet passage in the header. The inlet passage in the header is separated from the outlet by a diaphragm g —Fig. 1. When the flanged return bend f with the inner tube attached is bolted in position, the steam 110 enters the inlet passage b' , passes down the inner tapered tube d —Fig. 3—and exhausts through the outlet b —Fig. 1—by way of the annular space e —Fig. 1—between the inner and outer tubes. When the flanged return bend f —Fig. 1—is removed, the slots in the flanges permitting the easy and sidewise removal of the bolts and nuts, the inner tapered tube is withdrawn and the internal 115 part of the outer tube is exposed to view and can be dealt with for inspection or cleaning purposes or for renewal.

120 In order that the superheater tubes shall be heated by an increasing graduation of temperature from steam inlet to outlet, I 130

arrange the superheater tubes as follows:— The inlets of any desired number of superheater tubes as hereinafter described may be connected up to a collecting inlet header *h*—
 5 Figs. 16 and 17—and their outlets connected up with the inlets of another parallel row of superheater tubes, and so on indefinitely, the last row of outlets being connected with a collecting outlet header *j*—Fig. 16. In
 10 the form of header shown in Fig. 17, no extra collecting header is required, as both inlet and outlet form distributing and collecting headers themselves.

In order that the steam passing through
 15 the superheater tubes shall absorb all the heat possible from the furnace gases, I make the annular space *e*—Fig. 1—between the inner and outer tubes of small cross section, so that the whole body of steam is subjected
 20 throughout to the heat surrounding the outer tubes.

In order to provide the greatest possible protection to the parts of the superheater tubes which are subjected to the hottest furnace gases, the outer tubes may have removable jackets *r*—Fig. 18—of highly refractory material which can be cylindrical or of thimble or conical shape so that they can be easily removed or replaced.

The outer chamber *a* is by its flanged end secured to the inner flange of the collecting header *c* which is formed with a passage *b*—Fig. 20—and through said passage and into the chamber *a* are passed the inner tubes *d*,
 35 said tubes *d* being carried by the independent and rectangular flange *f*². This flange *f*² abuts against the other flange of the header *c* and against such flange abuts the rectangularly shaped return bend *f*, said
 40 bend, independent flange and header being bolted together by bolts taking in the slots (not shown in said Figs. 20, 21 and 22). To the upper part of the bend *f* is bolted the distributing header *h*, which header *h* is provided with a rectangular T-shaped passage
 45 and openings *b'*. Steam enters by way of passage *b'* in the inlet or distributing header *h*, passes down through the passages *b'* in the return bend *f* to the inner tubes *d* in chamber *a*, then through annular space *e* to outlet *b* of the collecting or outlet header *c*.

All flanges of header, bends or the like are provided with diagonal slots as shown in
 55 the various figures instead of holes so that the bolts can be withdrawn sidewise instead of longitudinally. This facilitates the removal of the bolts, and consequently the flanges, if said bolts should be burnt and
 60 the screw threads destroyed.

In Figs. 23 and 24 is shown how the distributing headers *h* and the collecting headers *c* may be made to form circles or arcs of circles with the superheater tubes pointing
 65 toward the center, the outer tubes *a*, if de-

sired, being provided with removable highly refractory jackets or cones *r*—Fig. 19—and as the working is practically the same as in the previous arrangement, further description is deemed unnecessary.

70

This form of superheater is especially suited for round flues, such as are in use with vertical boilers.

The outer tubes of compound or double superheater tubes have been protected by
 75 their being embedded in refractory material and no claim is made to such arrangement, as such refractory material does not constitute a removable jacket.

Having now described my invention, what
 80 I claim as new and desire to secure by Letters Patent of the United States is:—

1. A superheater unit including in combination with a header having inlet and outlet openings, a closed heater tube in communication with the outlet opening of the header, and an inner vapor tube extending longitudinally within the outer tube and in communication with the inlet opening of the header, said tubes being arranged in
 85 spaced relation to provide a gradual increase of the sectional area through the tubes from the inlet to the outlet.

2. A superheater unit including in combination with a header having inlet and outlet openings, a closed heater tube in communication with the outlet opening of the header, and an inner vapor tube arranged within the outer tube to provide between it and said outer tube a steam passage of flaring width whereby that part of the outer tube which is spaced farthest from the inner tube is subjected to the greatest heat.

3. A superheater unit including a header having a horizontal passage-way in communication with a right angularly disposed outlet passage, and also having an inlet passage, a plate adapted to be fitted to one side of the header, an outer tube carried with said plate and adapted to fit over one end 105 of said horizontal passage way of the header, a detachable cap member fitted to the other side of said header and having a passage way for registering with the inlet passage of the header, and an internal tube carried 110 by said detachable member and projecting through the header and into the outer tube.

4. A superheater unit including a header having a transverse passageway and a longitudinal passageway in communication therewith, and also having another longitudinal passageway which opens at the side of the header, an external tube closed at one end and fitted to the transverse passageway of the header, a member having a curved 120 passageway, one end of which communicates with the end of the passageway in the header that opens at the side thereof, and an internal tube carried by said member and in communication with the other end of said 130

4
curved passageway therein, said tube projecting through the transverse passageway of the header and into the external tube.

5. A superheater unit including a header having a raw steam inlet passage and a superheated steam outlet passage, a tube closed at one end and in communication with said superheated steam passage, a detachable fitting having an interior U-passage, an inner tube supported by said fitting and adapted to project through the superheated

steam passage of the header and into said outer tube, and the said U-passage of the fitting communicating with the raw steam inlet of the header.

15

In testimony whereof I have affixed my signature this 2nd day of March, 1917.

FREDERICK OATLEY BYNOE.
